DESCRIPTION

U.S. PATENT DOCUMENTS

FIG. 1 depicts a front, upper, right perspective view of a
sprayer showing the claimed design.

FIG. 2 depicts a rear, upper, left perspective view thereof.

FIG. 3 depicts a front elevation view thereof.

FIG. 4 depicts a rear elevation view thereof.

FIG. 5 depicts a left side elevation view thereof.

FIG. 6 depicts a right side elevation view thereof.

FIG. 7 depicts a top plan view thereof.

FIG. 8 depicts a bottom plan view thereof; and,

FIG. 9 depicts a front, bottom, right perspective view
thereof.

The dash lines depict portions of the sprayer forming no part
of the claimed design.

1 Claim, 8 Drawing Sheets
